DESIGN FOR AN ASH TRAY

Roderick W. Hoag, Melrose, Mass.

Application April 5, 1947, Serial No. 138,176

Term of patent 14 years

(Cl. D85—2)

To all whom it may concern:

Be it known that I, Roderick Wm. Hoag, a citizen of the United States, residing at Melrose, in the county of Middlesex, Commonwealth of Massachusetts, have invented a new, original, and ornamental Design for an Ash Tray, of which the following is a specification, reference being had to the accompanying drawing, forming part thereof.

In the drawing:

Fig. 1 is a top plan view of an ash tray, showing my new design.

Fig. 2 is a side elevation thereof.

Fig. 3 is a perspective view of the ash tray.

Fig. 4 is a partial section of 4—4 of Fig. 1.

I claim:

The ornamental design for an ash tray, as shown.

RODERICK WM. HOAG.
